UNITED STATES PATENT OFFICE.

JAMES P. WILLIAMS, OF NEW CASTLE, PENNSYLVANIA.

DESIGN FOR A PICTURE-HOOK.

SPECIFICATION forming part of Design No. 33,497, dated November 6, 1900.

Application filed July 25, 1900. Serial No. 24,824. Term of patent 14 years.

To all whom it may concern:

Be it known that I, JAMES P. WILLIAMS, a citizen of the United States of America, residing at New Castle, in the county of Lawrence and State of Pennsylvania, have invented and produced a certain new and original Design for a Picture-Hook, of which the following is a specification, reference being had therein to the accompanying drawing.

- 5. o My invention relates to a certain new and novel design for a picture-hook; and it consists in the shape and ornamentation as fully set forth in the drawing, which shows a perspective view of my new and original design.
- 15. o In the drawing, 1 indicates a substantially heart-shaped plate, which is provided with a series of apertures 2 and has an extension 3 at its upper end, this extension 3 terminating in a segment-shaped hook member 4, provided

at the top of its curve with an aperture 5. 20 The outer faces of the extension 3 and of the heart-shaped plate 2 are provided with an ornamental scrollwork 6 of fanciful pattern, the plate 1 also having scrollwork 7 appropriately placed between the apertures 2. 25

The extension 3 is provided with an opening 8 at a point close to its junction with the plate 1.

What I claim is—

The design for a picture-hook, substantially 30 as shown and described.

In testimony whereof I affix my signature in the presence of two witnesses.

JAMES P. WILLIAMS.

Witnesses:

JOHN NOLAND,
A. M. WILSON.
